UNITED STATES PATENT OFFICE.

ROBERT P. HASSSLER, OF AKRON, OHIO, ASSIGNOR TO THE B. F. GOODRICH COMPANY,
OF NEW YORK, N. Y., A CORPORATION OF NEW YORK.

METHOD AND APPARATUS FOR MARKING RUBBER STRIPS.

1,395,410.

Specification of Letters Patent.

Patented Nov. 1, 1921.

Application filed August 1, 1921. Serial No. 488,751.

To all whom it may concern:

Be it known that I, ROBERT P. HASSSLER, a citizen of the United States, residing at Akron, in the county of Summit and State 5 of Ohio, have invented a certain new and useful Method and Apparatus for Marking Rubber Strips, of which the following is a specification.

This invention relates to means for im- 10 pressing a design such as a name or a trademark in the surface of a raw rubber article, and more particularly raw rubber in strip form extruded from a tubing machine, and its object is to enable this operation to be 15 rapidly and effectively performed and the marking preserved during the subsequent vulcanization of the article.

Of the accompanying drawings, Figure 1 20 is a side elevation, partly in section, showing an apparatus constructed according to my invention and adapted to carry out the steps thereof.

Fig. 2 is an edge view of the marking ma- 25 chine taken from the plane 2—2 of Fig. 1.

Fig. 3 is an enlarged view, partly in sec- 30 tion, showing a portion of the marking drum and pressure-roller with the work in progress of being marked.

Fig. 4 is a view of the rubber strip with 35 the marking impressed thereon.

In the drawings, 10 is the delivery end of an ordinary tubing machine, and 11 is the raw rubber strip extruded therefrom, being 40 in this instance a round strip of tubular form, such as is used for perambulator tiring. 12 is a drum whose upper surface is located in line with and slightly above the level of the outlet from the tubing machine, said drum carrying a set of short needles or 45 marking points 13 adapted to form shallow pits or indentations in the under surface of the rubber strip, these pits forming the lines of the design 14 to be impressed on the strip, in this instance a series of letters forming a 50 word, the action being progressive as the drum rolls against the strip. 15 is a presser-roller suitably spaced from the upper portion of the drum for pressing the rubber strip against the surface of the drum in order 55 to cause penetration of the needles, the shaft of this roller being carried by an apertured bracket 16, slidable vertically on an arm 17 which forms a part of the machine frame or standard 18, and adapted to be fixed 55 at different heights thereon by means of a

set-screw 19. The standard 18 also carries a horizontal arm 20, on which is mounted a horizontally-adjustable guide 21 for the strip passing onto the drum, and another horizontal arm 22 which carries a grooved idle- 60 roller 23 for guiding the strip as it leaves the drum.

The drum 12 turns upon a shaft 24 carried by the supporting standard, and is driven by a belt 25 from a small pulley 26 rotated 65 by gearing in a box 27 from the shaft of an electric motor 28, the motor and gear-box being carried by a bracket 29 shiftable vertically on the supporting standard and held by a set-screw 30, whereby the tension on the 70 belt may be adjusted. The standard 18 is carried by a base 31.

32 is an open-topped box, pan or trough supported by frame-work 33 and containing a body 34 of powdered, earthy material such as soapstone, through which the marked strip is passed for the purpose of filling the pits constituting the marking 14 in order to prevent their closure by the softening of the rubber during subsequent vulcanization. 75

The strip 11, issuing from the soapstone trough 32, is received and coiled or rolled up in any suitable way, and is then vulcanized in the usual manner without a mold, the preferred method being to pack it in 80 soapstone in a box, and apply heat in the usual way at vulcanizing temperature.

From the foregoing description the operation will be evident, the raw rubber strip 11 as it issues from the tubing machine 10 85 being carried through the guide 21 onto the surface of the drum 12 and having its under surface indented at regular intervals by means of the needles 13 operating in conjunction with the presser-roll 15 in order to 90 impress an intaglio design such as 14 in the rubber in the form of lines of small pits. The marked strip then passes over the grooved idle-roller 23 and into the body of soapstone 34 in the trough 32, whereby the 95 pits become filled with soapstone, after which the strip is coiled (or it might be cut into lengths without coiling) and vulcanized as previously described. The use of the marking needles acting progressively in the 100 manner set forth enables me to impress the desired marking on the surface of the strip without unduly deforming it.

Various changes may be made in the de- 110 scribed mode of embodiment without de-

parting from the essential features of the invention.

I claim:

1. The method of marking rubber strip stock which comprises progressively impressing an intaglio marking in the surface of the raw rubber strip, filling the impressions to prevent their closure, and vulcanizing the strip without a mold.

10 2. The method of marking rubber strip stock which comprises rolling a set of marking needles against the raw strip, and vulcanizing the strip in conjunction with a filler to prevent the closure of the needle 15 pits.

3. The method of marking rubber strip stock which comprises progressively impressing an intaglio marking in the surface of the raw strip, filling the impressions with 20 a powder, and vulcanizing the strip.

4. The herein-described method which comprises extruding a raw rubber strip from a tubing machine, rolling an intaglio marking into the surface of the strip as it 25 issues from the machine, passing the marked strip through powdered soapstone to fill the impressions, and vulcanizing the strip.

5. The method of marking rubber articles which comprises indenting the surface of 30 the rubber with a design whose lines consist of a multiplicity of small pits, filling these pits with mineral powder, and vulcanizing the article in mineral powder.

6. The herein-described method which comprises extruding a rubber strip from a 35 tubing machine, rolling a set of marking needles against the raw strip as it issues from the machine, passing the marked strip through powdered earthy material to fill the pits, and vulcanizing the strip in powdered 40 earthy material.

7. In rubbing - marking apparatus, the combination of a tubing machine, means for progressively indenting a design in the surface of the raw strip issuing from said machine, and means for progressively filling the impressions with powdered material.

8. In rubber - marking apparatus, the combination of a drum having a set of marking needles, means for supplying raw 50 rubber in strip form to said drum, means for pressing the strip against the drum to cause penetration of the needles, and means for progressively filling the needle pits with powdered material.

9. In rubber - marking apparatus, the combination of a tubing machine, a drum having marking needles on its surface for receiving the raw strip from said machine, means for rotating said drum to propel the 60 strip, and a soapstone trough arranged beyond said drum through which the marked strip is passed.

In witness whereof I have hereunto set my hand this 27th day of July, 1921.

ROBERT P. HASSSLER.
